UNITED STATES PATENT OFFICE.

OSWALD S. PULLIAM, OF PITTSBURG, PENNSYLVANIA.

FRICITION DRAFT-RIGGING.

No. 839,783.

Specification of Letters Patent.

Patented Dec. 25, 1906.

Application filed February 26, 1906. Serial No. 302,996.

To all whom it may concern:

Be it known that I, OSWALD S. PULLIAM, a citizen of the United States, residing at Pittsburgh, in the county of Allegheny and State of Pennsylvania, have invented new and useful Improvements in Friction Draft-Rigging, of which the following is a specification.

The object of my invention is to provide a new and improved friction draft-rigging; and to this end my invention consists of a friction draft-rigging, in the novel features of construction, and in the combination of parts, all as fully hereinafter described and claimed.

In the accompanying drawings, which illustrate an application of my invention, Figure 1 is a top plan of a friction draft-rigging constructed in accordance with my invention; Fig. 2, a vertical sectional view, the section being taken on line II II of Fig. 1; and Fig. 3 a sectional view taken on line III III of Fig. 1.

Referring to the drawings, 1 designates a draw-bar, and 2 an extension or yoke attached to the rear end of the draw-bar by bolts 3. These parts are located between the draft-sills 4 of a car, and said draft-sills are formed with or provided with stop-plates 5, having inwardly-projecting flanges 6. The function of stop-plates 5 is to limit the travel of two follower-plates 7 and 7^a.

Located between and in contact with the followers 7 and 7^a I employ an outer main spring 8. Within the main spring 8 is a supplemental spring 9. Spring 9 is of less length than spring 8 and is otherwise considerable smaller than said spring 8.

Arranged between main spring 8 and the supplemental spring 9 is a series of friction or wedging plates on bars 10. In the form of my invention as illustrated I have shown four of these friction-plates, but do not desire to be limited to the number shown. These plates are formed with outer and inner corrugated or grooved contacting surfaces 11 and 12, said outer contacting surfaces 11 being in frictional contact with the coils of the main spring and the inner contacting surfaces 12 in frictional contact with the supplemental spring.

From the drawings it will readily be seen

that pressure exerted upon the follower-plates 7 or 7^a in either direction will tend to compress the outer spring. This compression of the main spring moves the friction-plates 10 inwardly against the inner spring, causing a separation of the coils of said spring and creating a tension on the inner or supplemental spring, which movement causes a tension on the supplemental spring.

By the form shown I produce a compression of the main spring, a tension on the supplemental spring, and provide in addition thereto the frictional contact-surfaces 11 and 12.

What I claim is—

1. A friction draft-rigging comprising a main spring, a supplemental spring, and a movable wedge plate or block interposed between and in frictional contact with the springs arranged to be moved against the supplemental spring upon a compression of the main spring.

2. A friction draft-rigging comprising an outer main spring, an inner supplemental spring, and a movable wedge plate or block interposed between and in frictional contact with the springs arranged to be moved inwardly against the inner spring upon a compression of the outer spring.

3. A friction draft-rigging comprising a main spring, a supplemental spring, and a movable corrugated plate interposed between and in frictional contact with the springs.

4. A friction draft-rigging comprising a main spring, a supplemental spring, and a series of corrugated or grooved plates interposed between and in frictional contact with the springs.

5. A friction draft-rigging comprising followers, an outer spring located between and in contact with the followers, an inner spring of less length than the outer spring, and a friction-plate interposed between and in contact with the springs arranged to create a tension on the inner spring upon the compression of the outer spring.

6. A friction draft-rigging comprising an outer spring, an inner spring, and a friction-plate between and in contact with said springs arranged to create a tension on the

inner spring upon the compression of the outer spring.

7. A friction draft-rigging comprising an outer spring, an inner spring, a plurality of grooved plates located between and in frictional contact with the springs and adapted to create a tension on the inner spring upon a compression of the outer spring.

In testimony whereof I affix my signature in presence of two subscribing witnesses.

OSWALD S. PULLIAM.

Correction in Letters Patent No. 839,783.

It is hereby certified that Letters Patent No. 839,783, granted December 25, 1906, upon the application of Oswald S. Pulliam, of Pittsburgh, Pennsylvania, for an improvement in "Friction Draft-Rigging" were erroneously issued to "said Pulliam" as owner of said invention; that said Letters Patent should have been issued to *Pittsburgh Equipment Company, of Pittsburgh, Pennsylvania, a corporation of Pennsylvania*, as assignee of the entire interest in said patent, as shown by the record of assignments in this office; and that the said Letters Patent should be read with this correction therein that the same may conform to the record of the case in the Patent Office.

Signed and sealed this 22d day of January, A. D., 1907.
